TIME DIVISION MULTIPLEX COMMUNICATION SYSTEM

John H. Homrighous, Oak Park, Ill.

Application January 12, 1943, Serial No. 472,105

12 Claims. (Cl. 250—9)

1

This invention relates to improved methods and systems for transmitting a number of messages simultaneously through a single transmission channel.

One of the main objects of my invention is to provide a system for intermittently transmitting two or more like or different messages, such as, sound, pictures, telegraph, written or coded signals over a single carrier.

Another object of my invention is to provide an improved means whereby signals representative of different messages may be recorded and reproduced at a different speed for the intermittent transmission and reception of the different message signals over a common path.

Message in this specification is to be understood to include any intelligence represented by sound, picture, or code signals.

Several methods for transmitting a number of messages on a single carrier have been devised. These systems employ mechanism such as, electromagnets or rotating devices which have a definite operating time, thus limiting the number of messages that may be transmitted intermittently over a single carrier. In one method of my present invention I provide electronic devices having no mechanical moving parts for controlling the intermittent transmittal of two or more different messages. In this system the fragments of each message may be separated and again joined at a very rapid rate. In a second method equal portions or fragments of signals representative of two messages may be recorded and reproduced at a greater speed so that both messages may be transmitted in successive rotation over a common path.

In this invention I also employ a new electron tube which I choose to call an "off and on electron relay." This tube will open or close a circuit, that is, it opens or closes the electron path within the tube, giving a very sharp cut off.

Other objects and advantages of my invention will appear from the following description, taken in connection with the accompanying drawings, in which:

Figures 1 and 9 are simplified diagrammatic views of a radio transmitting station and a radio receiving station respectively, illustrating the principles applied in this invention.

Figure 2 is a detail view of the off and on electron relay tube.

Figure 3 is a detail end view of the tube in Figure 2.

Figure 4 shows a circuit arrangement for the off and on electron relay tube.

Figure 5 is a diagrammatic arrangement of the message distributor and associated circuits illustrated in Figure 1.

Figure 6 is a detail view of the message recording and reproducing mechanism shown in Figure 1.

Figure 7 is a detail view of a sound track film used in Figure 6.

Figure 8 is a detail view of the scanning device used in Figure 6.

Figure 10 is a diagrammatic arrangement of the message distributor and associated circuits illustrated in Figure 9.

Figure 11 is a detail view of the message recording and reproducing mechanism shown in Figure 9.

Figure 12 is a detail view of a sound track film used in Figure 11.

Figure 13 is a detail view of the scanning device used in Figure 11.

In Figure 1, the numerals 1 and 2 designate microphones and 3 designates a microphone or a telegraph instrument where electrical signals are developed and supplied to the amplifiers 4, 5, and 6 respectively. These signals are fed intermittently to the modulation amplifier 7.

A carrier wave is provided by an oscillator 8. In the power amplifier 9 this carrier wave is modulated by the sound and telegraph signals and also by synchronizing signals or impulses from the message distributor apparatus 10 through the modulation amplifier 7. The signals from the power amplifier 9 are supplied by a connection 11 to the antenna 12.

Sound signals, telegraph signals, and control signals may be transmitted on the same carrier. While I have shown electrical signals from three separate communications modulated on a single carrier, it is to be understood that the signals

from several more separate communications may be intermittently modulated on a single carrier where the rate of change from one message to another message is of a greater frequency than the electrical signals produced by sound and the intermittent fragments of the messages are only for a short interval.

In transmitting only two messages a somewhat slower rate of change from one message to another message may be employed and each fragment or intermittent part of a message may be recorded and reproduced at a greater speed for transmittal so that both messages may be alternately modulated on a carrier without the loss of any part of the message. In order to accomplish this feature the electrical signals from the

amplifiers 5 and 6 are applied through switches 13 and 14 to the recorders or glow lamps 15 and 16 for registering variable light intensities forming separate sound tracks on a movable memory or fluorescent film. The variable light intensities registered on the film are separated into equal parts in the interval reducing mechanism 17 and reproduced at one half their normal interval at 18 and 19' where they are fed to the amplifiers 19 and 20 and then applied to the modulation amplifier 7 through the switch 21.

Figures 2 and 3 show a new off and on electron relay tube used in Figures 5 and 10 to govern the beginning and the ending of the several parts of a message. This tube comprises an evacuated envelope or glass bulb 22 containing an indirectly heated cathode 23, two ray control electrodes 24 and 25 of narrow material located on opposite sides and parallel to the cathode, two anodes 26 and 27 located on opposite sides of the cathode and in alignment with the control electrodes 24 and 25. The anodes 28 and 29 located adjacent to the anodes 26 and 27 are connected together inside the bulb. The several tube elements are mounted on and held in proper position by the insulating member 30. The member 30 is secured by small rods 31 and 32 to the tubular glass stem 33. On the under side of the insulating member there may be a metal shield 34 connected to the cathode 23 and indicated by the dotted line in Figure 3. A metal shield 35 may also be placed over the top and connected to the lower shield by the rods 36 and 37 extending on the outside of anodes 28 and 29 as shown in Figure 3. These shields maintained at cathode potential will confine the electrons to the anodes. Conductors from the individual tube elements, three from the anodes, two from the control electrodes, and two from the filament are extended through the glass stem 33 to the base of the tube where they are brought out through the glass bulb and terminated on base pins extending from the tube base.

Referring to Figure 4 the operation is as follows, the anodes 26 and 27 are maintained at a higher positive potential than the anodes 28 and 29. The control electrodes 24 and 25 are operated at a variable or adjustable positive potential. Assuming that the control electrode 24 is at approximately the same potential as the anode 26 and control electrode 25 is at a much lower potential than the anode 27, then electrons will flow from the cathode 23 to the anode 26 through the load resistance 38. The electrode 25 being at a lower potential than the anode 27 will prevent or shield the electrons from reaching the anode 27. Then an increasing potential on the grid of tube 38', such as is produced by a saw tooth wave generator, will cause the potential on the control electrode 24 to become less positive which will deflect or shield the electrons from the anode 26 causing a sharp increase in potential across the load resistance 38 which may be used for many purposes, such as, controlling the energization of a relay, or triggering a tube to discharge a condenser. The increase of potential at load resistance 38 may be applied through a portion of resistance 39 to the second control electrode 25 increasing its potential sufficiently to cause the electrons to flow from the cathode 23 to the anode 27 which will cause a sharp voltage drop in its load resistance 40 which may be utilized to control other circuits.

As the voltage on grid of tube 38' decreases or when the saw tooth voltage is triggered the potential of the electrode 25 is restored to its less

positive condition and the potential of the electrode 24 is restored to its more positive condition. The above operation will be repeated for each wave in a series of saw tooth waves applied to the grid of tube 38' to be more fully explained later.

Thus from the above description it will be seen that this off and on electron relay device opens or closes an electron path through the tube, thereby giving a quick cut-off or abrupt current change.

Referring to Figure 5 the apparatus 10 for collecting the fragments of several messages so that they may be transmitted on a single carrier comprises a condenser 41 charged through an adjustable resistance 42 from a positive potential source as indicated. By movement of the switches 43 and 44 another condenser 45 may be charged through resistance 46 from a high positive potential source to change the interval for the voltage to build up to a certain value. Charging current control may also be obtained by varying the resistances through the movable contacts 47 and 48 to give close adjustments. The condenser 41 or 45 may be discharged through the trigger tube 49 when the voltage builds up to a predetermined value to be explained later. The condenser 41 or 45 may be repeatedly charged from the source of potential and discharged through the trigger tube 49 to produce successive saw tooth voltages or saw tooth waves in a manner well known to those skilled in the television art.

When the condenser 41 or 45 becomes charged, depending upon which switch contacts are closed, the saw tooth voltage wave in the plate circuit of tube 49 is impressed on the grid 50 of the multi-unit amplifier tube 51 through an adjustable contact 52 on the voltage dividing resistance 53, and by the adjustment of contact 52 the amplitude of the saw tooth wave may be controlled. The outputs of the amplifier tube 51 supplied to the load resistances 54 and 55 will gradually increase the potential on the grids 56, 57 and 58 of tubes 59, 60 and 61 respectively. Tubes 59, 60 and 61 are biased so that maximum current through their load resistances will be at different intervals for a gradual increase of potential on their grids. That is, tube 59 is biased so that the current through the load resistance 62 will be approximately maximum value after a short interval of time with no appreciable change of current in the tubes 60 and 61 during this interval. In tube 60 having a greater negative bias, current will become approximately maximum value through its load resistances 63 after a greater interval of time, and in tube 61, having the largest negative bias, the current through its load resistance 65 will become maximum value a short interval of time after the peak value of current flows through the preceding tube 60. These tubes or the bias on the tubes may be arranged to give any desired interval of time before reaching their maximum current flow, or maximum potential drop through their load resistances. Also other tubes may be added at 66 to give a greater number of intervals of the time for the duration of one saw tooth voltage wave.

The large current through the load resistance 62 causes a voltage drop to be applied to the control electrode 67 of the off and on electron relay tube 68. This change lowers the potential on the electrode 67 below the potential on the anode 69 which causes, first, an increase of poten-

tial on control electrode 70 through a portion of the resistance 71 and adjustable contact 72. The increase of potential on electrode 70 to approximately the same potential as that of anode 73 will permit the electrons to flow from the cathode to the anode 73 causing a drop in potential in the load resistance 74 which is applied to the grid 75 of tube 4 thus blocking the electrical signals from the microphone 1 during the time current is flowing through the load resistance 74; second, the potential change on electrode 67 causes the deflection of the electrons from the anode 69 thus raising the potential at the load resistance 76 which is applied to the grid 77 of the amplifier tube 5 rendering this tube operative to the signals produced by the microphone 2.

A short interval after the current in tube 59 has reached its peak value the amplifier tube 60 will function to increase the current flow in load resistance 63 and reduce the current flow in resistance 64 thereby lowering the potential on the control electrode 77 and increasing the potential on the electrode 78 of the off and on relay tube 79. This tube will produce an increase of current in load resistance 80 to cause a decrease of potential on the grid 81 of tube 5 thus rendering this tube inoperative to the electrical signals from the microphone 2, and at the same time by the decrease of current in load resistance 82 it will increase the potential on the grid 83 of tube 6 rendering this amplifier responsive to the electrical signals produced by the telegraph instrument 3.

The signals from the telegraph instrument 3 will continue until the current in tube 61 reaches approximately its peak value, whereupon the voltage drop developed across the load resistance 65 and applied to the control electrode 84 of tube 85 will prevent electrons from flowing to the anode 86, thus increasing the potential on the control electrode 87, which will produce a voltage drop at the load resistance 88 which is applied through coupling condenser 89 to the grid 90 of the modulation amplifier 7 to develop a high amplitude signal or synchronized pulse to control the receiving stations to be explained later. The high positive potential developed at the load resistance 91 is applied through coupling condenser 92 to the grid of the trigger tube 49. This high potential pulse causes tube 49 to become conductive thereby discharging the condenser 41 and restoring the apparatus and associated circuits to their normal condition or starting point to thereafter continually repeat the same operations. The anodes of the different amplifiers 4, 5, and 6 are connected in parallel through condenser 93 to the grid 90 of the modulation amplifier 7. Thus by rendering the individual amplifiers inoperative for certain definite periods of time the electrical communication signals may be intermittently modulated on a single carrier.

From the above description it is shown that the message distributor divides and collects parts of different communications and modulates them intermittently on a carrier; this system is not limited to three communications but there may be more depending upon the frequency of the saw tooth wave generated, which may be several times higher than the frequency of speech communication.

With reference to Figure 6 I have shown mechanism for increasing the frequency of signals such as those developed by the microphone or telegraph instruments by first recording them on a moving

film having a coating of fluorescent material and then reproducing these signals by mechanism or a scanning device moving in the reverse direction. Instead of the film, wires may be employed with magnetic devices for recording and reproducing the signals. The film 94 may be of translucent material provided with a coating of fluorescent material activated by light from a conventional glow lamp or a lamp may be used with ultraviolet light predominating. In place of the glow lamp a light valve similar to that shown in my application Serial #306,537, filed November 28, 1939, now Patent No. 2,309,393, issued Jan. 26, 1943, may be used.

15 The reducing mechanism consists of a container or a light proof box 95 shown with one side removed for clearness, having an endless film 94 coated with fluorescent material and arranged to be rotated downward past the recorder or glow lamp 15 for recording a message on the film. Another glow lamp 16 is behind the glow lamp 15 in Figure 6, and, illustrated in Figure 7. This lamp is for recording a second message on the film 94. As previously explained in connection with Figure 20 1 the microphones 2 and 3 through the amplifiers 5 and 6 and switches 13 and 14 may actuate the glow lamps 15 and 16 respectively in accordance with the messages to be transmitted. The glow lamps 15 and 16 may be provided with caps each 25 having a very narrow slot exposed to the film for recording the changes of light intensities on the film in the form of variable intensity sound tracks or variable brilliancy of the fluorescent material as illustrated at 96 and 97 in Figure 7. 30 Back of the film 94 is a scanning mask screen 98 arranged to be rotated in the opposite direction to that of the film and provided with small projecting light valves 101 and 102 having a narrow slot to project only parallel rays of light toward 35 the film. These light valves or light ray control members 101 and 102 are rotated one at a time past the lamp 99.

The film and scanning screen may be divided into sections or frames as shown by the horizontal 40 lines 100 in Figures 7 and 8. The light valve 101 projecting light to one sound track will appear in every other frame in the scanning screen, and the light valve 102 for the other sound track will appear in alternate frames or fields.

45 50 The lamp 99 and lens 103 are located in a separate light proof compartment being approximately the height of one frame. As the film is moving downward and the scanning screen is moving upward at the same time, light from the 55 lamp 99 will be projected alternately to the sound tracks 96 and 97 to increase or intensify the variable glow in the fluorescence material so that light rays alternately reflected by the mirrors 104 and 105 from the sound tracks may actuate the photo cells 18 and 18' respectively.

60 The motor 106 drives the sprocket wheel 107 to rotate the film in a clockwise direction. The sprocket wheel 108 is driven by the wheel 107 but in the opposite direction. One complete 65 revolution of the sprocket wheel moves the film a distance of four frames. Therefore some means for synchronizing the movement of the film with the frequency of the saw tooth wave must be provided. In order to accomplish this feature I provide a relay 109 located in the box 95 and operated at the same time that the message distributor mechanism 10 is restored to its starting 70 condition to govern the movement of the scanning screen.

75 As previously explained in connection with Fig-

ure 1, when transmitting only two messages, a slow rate of change from one message to another message may be employed. That is, the frequency of the saw tooth wave may be adjusted by the switches 43 and 44 and the associated resistances to produce any desired frequency such that will conform to the movement of the film which may be maintained at substantially the speed of television pictures or approximately thirty frames per second.

Tubes 59 and 68 will be inoperative by opening the switches 116 and 117 when using the film for reducing the interval of the parts or fragments of messages.

The film is rotated inside the box 95 for ageing or for restoring it to its normal conditions. The fluorescent material coating may have a short decay time and the film may be run over idle pulleys to give greater time before being again exposed to the glow lamp.

The operation is as follows: The positive pulse that triggers the tube 49 Figure 5 is also applied to the grid of tube 110 through the switch 111. The switch 111 is thrown to the off position when the reduction mechanism 17 is not employed. This impulse supplied to the grid of tube 110 permits sufficient current to flow through relay 109 for operating its armature to move the pin 112 out of engagement with the pin 113 in the sprocket wheel 108. The scanning screen 93 is driven at such speed that the screen will travel the distance of two frames in slightly less time than the duration of one saw tooth voltage wave. In that case the pin 113 in sprocket wheel 108 would engage the pin 112 on the armature of relay 109 thus holding the scanning screen momentarily through the friction clutch indicated by the circle 114. The operation of the relay 109 disengages the pins and permits the scanning screen to move again the distance of two frames whereupon the pin 112 will momentarily engage the pin 115. Thus the movement of the scanning device will be automatically synchronized with the saw tooth voltage waves.

With reference to Figure 9 showing a receiving station, the antenna 120 receives the carrier signals from the transmitter antenna 12 and transfers them to a radio frequency amplifier 121. An electrical oscillator 122 reacts with these signals in the first detector stage 123 on the super-heterodyne principle to produce an intermediate frequency which is supplied to the intermediate stage 124. After suitable amplification the sound signals and the synchronizing signals are detected at 125 and the sound signals are supplied to the power amplifier 126, 127 and 128 one at a time. After suitable amplification in these power amplifiers the sound signals may be supplied to loud speakers 129, 130 and 131, or a telegraph instrument may be employed at 131.

The control or synchronizing signals are applied to the synchronizing frequency amplifier 132 and after suitable amplification they are supplied to the message distributor 133 to control the periods of the saw tooth voltage waves developed therein to be explained later.

Sound signals, telegraph signals and control signals may be detected at 125. While I have shown three separate paths for the reception of communication signals, several more separate communications may be intermittently received where the rate of change from one message to another message is very high. In the reception of only two messages where the normal interval for each message has been reduced and it is required

that these messages be expanded for conveying intelligence, then the sound signals from the detector 125 are applied through switches 134 and 135 to the recorder or glow lamps 136 and 137 for registering variable light intensities on a movable memory or fluorescent film. The variable light intensities registered on the film are separated into equal parts in the interval expanding or recording and reproducing mechanism 138 and 10 reproduced at 139 and 140 as electrical signals and at their normal interval where they are fed through switches 118 and 119 to the amplifiers 127 and 128.

Referring to Figure 10 the apparatus 133 for separating the fragments of several messages into separate and distinct messages similar to the apparatus 10 at the transmitter, comprises a condenser 141 charged through an adjustable resistance 142 from a positive potential source as indicated. By movement of the switches 143 and 144 another condenser 145 may be charged through resistance 146 from a high positive potential source to change the period for the voltage to build up to a certain value. Charging current control may also be obtained by varying the resistances through the movable contacts 147 and 148 to give close adjustments. The condenser 141 or 145 may be discharged through the trigger tube 149 when the voltage builds up to a predetermined value to be explained later. The condenser 141 or 145 may be repeatedly charged from the source of potential and discharged through tube 149 to produce a series of saw tooth waves in a manner well known particularly in television.

When the condenser 141 or 145 becomes charged, depending upon which contacts are closed, the saw tooth voltage wave in the plate circuit of tube 149 is impressed on the grid 150 of the multi-unit amplifier tube 151 through an adjustable contact 152 on the voltage dividing resistance 153, and by this adjustment controlling the amplitude of the saw tooth wave. The outputs of the amplifier tube 151 supplied to the load resistances 154 and 155 will gradually increase the potential on the grids 156, 157, and 158 of tubes 159, 160, and 161 respectively. Tubes 159, 160, and 161 are biased so that maximum current through their load resistances will be at different intervals for a gradual increase of potential on their grids. That is, tube 159 is biased so that approximately maximum current will flow through the load resistance 162 after a short interval of time with no appreciable change of current in the tubes 160 and 161 during this interval. In tube 160 having a greater negative bias, current will become approximately maximum value through its load resistance 163 after a greater or second interval of time and in tube 161 having the largest negative bias, the current through its load resistance 164 will become approximately maximum value a short interval of time after the peak current flow through the preceding tube 160. These tubes or the grid bias on the tubes may be arranged to give the desired voltage drops in their plate circuits at predetermined intervals of time corresponding to the intervals for intermittent messages being transmitted. Other tubes may be added at 165 to give a greater number of communications that may be received over a single carrier, or a greater number of intervals for the duration of one saw tooth voltage wave.

The large current through the load resistance 162 causes a voltage drop to be applied to the control electrode 166 of the off and on relay tube 167. This change lowers the potential on the elec-

trode 166 below the potential on the anode 168 which causes first, an increase of potential on control electrode 169 through the resistance 170 and adjustable contact 171. The increase of potential on electrode 169 to approximately the same potential as that of anode 172 will permit electrons to flow from the cathode to the anode 172, causing a drop in potential in the load resistance 173 which is applied to the grid 174 of tube 126 thus blocking the electrical signals from the second detector 125 during the time current is flowing through the resistance 173; second, the potential change on the control electrode 166 causes the deflection of the electrons from the anode 168 thus raising the potential at the load resistance 175 which is applied to the grid 176 of the amplifier tube 127 rendering this tube operative to the signals from the second detector.

A short interval after the current in tube 159 has reached its peak value the amplifying tube 160 will function to increase the current flow in load resistance 163 thereby lowering the potential on the control electrode 177 of tube 178. This change lowers the potential on the electrode 177 below the potential on the anode 179 which causes an increase of potential on the control electrode 180 to approximately the same potential as that of anode 181 which will permit electrons to flow from the cathode to the anode 181 causing a drop in potential in the load resistance 182 which is applied to the grid 183 of the power amplifier tube 127, thus rendering this tube inoperative to the signals from the second detector during the time that peak current is flowing through the resistance 182. The potential change on the control electrode 177 causes the deflection of the electrons from the anode 179 thereby raising the potential at the load resistance 184 which is applied to the grid 185 of the amplifier tube 128 rendering this tube responsive to the signals from the second detector.

The signals from the second detector will continue to be amplified in tube 128 until the current in tube 161 reaches approximately its peak value, whereupon the voltage drop developed across the load resistance 164 and applied to the control electrode 186 of tube 187 will prevent electrons from flowing to the anode 188 thereby increasing the potential on the control electrode 189 which will produce a voltage drop at the load resistance 190. The voltage drop at resistance 190 may be applied to the grid 191 of the power amplifier 128 to hold the tube momentarily non-responsive to sound signals while restoring the saw tooth wave generating circuits to their starting condition. The increased potential developed at the load resistance 192 may be applied through the coupling condenser 193 to the grid 194 of the trigger tube 149. This voltage impulse causes the tube 149 to become conductive thereby discharging the condenser 141 and restoring the saw tooth generating apparatus and associated circuits to their starting condition. However; upon the reception of synchronizing signals the tube 187 will not control the discharge of the condenser 141. This tube will only function during the absence of synchronizing signals resulting from fading or when tuning between stations or the receiver may be tuned to a certain carrier waiting for signals.

Sound and synchronizing signals are detected at tube 125. The sound signals may be applied to the control grids of the power amplifier tubes 126, 127, and 128 in parallel. Thus it is shown that each one of the speakers will be intermittently actuated by electrical signals from a sep-

arate message. The tube 132 is for controlling the duration of the saw tooth wave and it may be biased so that the sound signals will not produce plate current but it will respond to the synchronizing pulses transmitted at the end of each saw tooth wave. The synchronizing signals applied to the grid 195 may be amplified in the anode circuits and supplied through the coupling condenser 196 to the grid 194 of the trigger tube 149.

10 The period of the saw tooth wave or the interval of time between synchronizing pulses is arranged to be slightly shorter than the time required for the off and on relay tube 187 to control the discharge of the condenser 141; and in this manner the receiving stations are synchronized with the transmitter. To explain more specifically; the receiving stations are synchronized by utilizing the high amplitude impulses transmitted over the carrier at regular intervals to control the duration of each saw tooth voltage wave. That is; the impulses are employed to regularly restore the condenser charging apparatus and associated circuits to their start charging condition.

15 20 25 From the above description it is shown that the message distributor in the receiving station separates and collects the parts or fragments of a plurality of different messages received intermittently over a single channel into several separate and distinct messages.

30 35 40 With reference to Figure 11 I have shown mechanism for expanding the interval or decreasing the frequency of electrical signals produced by two separate and distinct messages by recording them on a moving fluorescent coated film, through the action of a scanning screen or device moving in the opposite direction.

45 The mechanism shown in Figure 11 is very similar to that explained in connection with Figure 6. 40 The film may be of translucent material provided with a coating of fluorescent material activated by light from a conventional glow lamp, or a light valve similar to that shown in my above mentioned application may be used.

50 55 60 65 The expanding mechanism comprises a container or light proof box 198, shown with one side removed for clearness, having an endless fluorescent coated film 197 arranged to be rotated downward past the reproducer or photo cell 139. The glow lamp 136 is for recording a message on the film 197 through the action of the scanning screen 199 rotated in a direction reverse to that of the film 197 but at approximately the same speed. Another glow lamp 137 is directly back of the lamp 136 and as illustrated in Figure 13 is for recording a second message on the film 197.

70 75 80 The film and scanning screen may be divided into sections or frames as shown by the horizontal lines 200 in Figures 12 and 13. The glow lamp 136 through the action of the rotating mirrors 201 projects light to the film forming one sound track 202 in all frames as illustrated in Figure 12; and the glow lamp 137 through the action of the rotating mirrors 203 projects light to the film forming a second sound track 204 in all frames.

85 The revolving scanning screen 199, back of the film 197, is provided with small reflecting mirrors 201 and 203 rotated one at a time, past the film to reflect light from the glow lamps to the film. As the film is moving downward and the mirrors on the scanning device are moving upward at the same time variable intensities of light from the glow lamps will be recorded on the film in two separate and continuous sound tracks. That is;

each mirror will spread the light variations over a space of two frames on the film.

The lamp 205 in a separate compartment, located below the recording mechanism, is for projecting light to the sound track 202 to increase or intensify the variable glow of the fluorescent material so that the increased glow from the sound track may actuate the photo cell 139 to reproduce one of the messages. Another lamp directly back of the lamp 205 is for projecting light to the second sound track to increase the glow in this track to actuate the photo cell 140 for reproducing a second message.

The motor 206 drives the sprocket wheel 207 to rotate the film in a clockwise direction. The sprocket wheel 207 drives the sprocket wheel 208 in a counterclockwise direction. One complete revolution of the sprocket wheels moves the film a distance of four frames. In order to synchronize the movement of the film with the frequency of the saw tooth wave and also with similar operations at the transmitter I provide a relay 209 located in the box 198 and operative each time that the synchronizing impulses restore the distributor mechanism 133 to its starting condition.

In Figure 10 the tubes 159, 167, and 126 will be inoperative by opening the switches 210, 211, and 212 when using the mechanism of Figure 11.

The film is rotated inside the light proof box 198 for ageing or for restoring it to its normal condition. The fluorescent material coating may have a short decay time and the film may be run over idle pulleys to give greater time before being again exposed.

The operation is as follows. The synchronizing pulses after suitable amplification in tube 132 are also applied to the grid of tube 213 through the switch 214'. The switch is opened when more than two conversations are being received or when mechanism 133 is idle. This impulse supplied to the grid of tube 213 permits sufficient current to flow through relay 209 for operating its armature to move the pin 214 out of engagement with the pin 215 in the sprocket wheel 208. The scanning device 199 is driven a distance of two frames in slightly less time than the interval between synchronizing pulses. Therefore, the pins 215 and 216 would engage the armature pin 214 alternately to hold or slow the movement of the screen 199 momentarily through the friction clutch indicated by the circle 217. The operation of relay 209 at the end of each two frames disengages the pins and permits the scanning device to continue its movement. Thus the movement of the scanning device will be automatically synchronized with the scanning device at the transmitter.

In the various circuits shown and described I have simplified the drawings by indicating the source of potential by a positive or negative sign. Also I have omitted the heater element from the various tubes.

The embodiments of the invention which have been given herein are illustrations of how the various features may be accomplished and of the principles involved. It is to be understood that the invention contained herein is capable of embodiments in many other forms and adaptations, without departing from the spirit of the invention and the scope of the appended claims.

Having thus described my invention, I claim:

1. In a multiplex communication system, a transmitter, means at said transmitter to produce a carrier wave, means at said transmitter to produce a first series of successive saw tooth

waves, including control signals to terminate the waves, means to select different recurrent periods of time in said saw tooth waves for controlling the transmission of different signals in the recurrent periods, said last means comprising apparatus and suitable circuits to select amplitude measurements in the said saw tooth waves for both initiating and terminating each of the said periods, means to transmit signals representative of different messages and said control signals modulated on said carrier wave during a number of the said recurrent periods, a receiver, means to receive said signals, means at said receiver to produce a second series of successive saw tooth waves under the control of said control signals, means to select recurrent periods in the said second series of saw tooth waves corresponding to said recurrent periods at the transmitter for controlling the reception of different signals in the said recurrent periods, said last means comprising a message signal amplifier for each of the said recurrent periods, and a plurality of relay tubes under control of said second series of saw tooth waves to interrupt substantially current through the several relay tubes in successive rotation for controlling said amplifiers to reamplify said signals representative of different messages in successive rotation.

2. In a multiplex communication system, a radio transmitter, means to produce a carrier wave, apparatus and suitable circuits associated with the said transmitter to produce a series of recurrent saw tooth waves, a source of current, a plurality of relay tubes each having at least an anode and a cathode connected to said source of current and an electron deflecting electrode controlled by amplitude measurements in each wave of the said saw tooth waves to substantially interrupt the anode cathode current in the several relay tubes in successive rotation, thereby, selecting a number of recurrent periods in said saw tooth waves, means to modulate said carrier wave with fragmentary portions of signals representative of a different message in each of the said recurrent periods, said last means comprising a modulation amplifier, and a number of message signal amplifiers, one for each recurrent period, connected in parallel to said modulation amplifier under control of said relay tubes, and mechanical switching means for adjusting said apparatus to vary the number of saw tooth waves in a given time, thereby varying the number of fragmentary portions of the signals in each of the said messages transmitted in a given time.

3. In a multiplex communication system, a radio transmitter, means to produce a carrier wave, apparatus and suitable circuits associated with the said transmitter to produce a series of successive saw tooth waves, a source of current, a plurality of relay tubes each having at least an anode and a cathode connected to said source of current and an electron deflecting electrode controlled by amplitude measurements in each wave of the said saw tooth waves to deflect the electrons away from the anode to interrupt substantially the anode cathode current in the several relay tubes in successive rotation, thereby, selecting a number of recurrent periods in said sawtooth waves, and means to modulate said carrier wave with fragmentary portions of signals representative of a different message in each of the said recurrent periods.

4. In a multiplex communication system, a radio transmitter, means at said transmitter to produce a carrier wave, apparatus and suitable

circuits associated with said transmitter to produce a first series of successive saw tooth waves including synchronizing signals, a source of current, a plurality of relay tubes each having at least an anode and a cathode connected to a source of current and an electron deflecting electrode under control of said sawtooth waves for deflecting the electrons away from the anode to substantially interrupt the anode cathode current in the several relay tubes in sequence, thereby, selecting a number of recurrent periods in the sawtooth waves, means to modulate said carrier wave with signals representative of a different message in each of the said recurrent periods and with synchronizing signals in another recurrent period, means to transmit said modulated carrier waves, a receiver, means to receive said modulated carrier wave, apparatus and suitable circuits associated with said receiver to produce a second series of successive saw tooth waves under the control of said synchronizing signals, a second source of current, other relay tubes each having at least an anode and a cathode connected to said second source of current and an electron deflecting electrode under control of said second series of sawtooth waves for deflecting the electrons away from the anode to interrupt substantially the anode cathode current in the said other relay tubes in sequence, thereby, selecting a number of recurrent periods in said second series of sawtooth waves corresponding to the selected periods at said transmitter, and means to demodulate the received carrier wave to produce message signals in each recurrent period in said second series of saw-tooth waves representative of a different one of said messages.

5. In a multiplex communication system, a radio station for transmitting a number of messages in successive rotation over a common path, means at said station to produce a series of successive saw tooth waves, including control signals for terminating the waves, message recording and reproducing means under the control of said control signals comprising a movable film coated with material sensitive to light and glow lamps for directing light rays toward the film for recording signals representative of a number of messages in narrow strips forming sound tracks thereon, with a source of light and light ray control members movable in a direction opposite from that of said film to direct other light rays from said source of light toward the said sound tracks, devices responsive to the recordings in said sound tracks to reproduce signals for each of the said messages in spaced periods of time, and a message distributor under the control of amplitude measurements in each of the said saw tooth waves to select recurrent periods of time for transmitting the said reproduced signals for a different one of said messages in each recurrent period.

6. In a communication system, a transmitter station, means at said station to produce a series of successive saw tooth waves including synchronizing signals to terminate the waves, message recording and reproducing mechanism to record message signals representative of a number of messages and to reproduce the signals at a greater speed relative to the speed of recording for intermittently grouping the signals for each of the several messages, a message distributor under the control of said saw tooth waves to control the periods of time for transmitting the grouped signals in each of the said messages, a receiver station, means at said receiver station to produce another series of saw tooth waves under the control of

said synchronizing signals, a message distributor at said receiver station under the control of said another series of saw tooth waves to control the periods of time for the reception of the grouped signals for each of the said messages, and another message recording and reproducing mechanism for recording said grouped signals and to reproduce the signals at a slower speed relative to the speed of recording for uninterrupted reception of the said messages.

7. In a communication system, a radio transmitter provided with apparatus and associated circuits to produce a series of successive saw tooth waves, a rotatable fluorescence coated film associated with said transmitter, a number of glow lamps to direct light rays of variable intensity corresponding to signals representative of a number of messages toward said film for producing several variable glow sound tracks thereon, a source of light, light ray control members movable in an opposite direction relative to said film to direct light rays from said source of light toward said sound tracks to intensify the variable glow, a photo electric device for each sound track sensitive to the intensified glow for reproducing said signals intermittently, means to produce a carrier wave, and a plurality of electron deflecting relay tubes controlled by said saw tooth waves to select a number of recurrent periods for modulating said carrier wave with said reproduced signals representative of a different one of said messages in each recurrent period.

8. In a communication system, a radio station, means at said station to produce a carrier wave, means at said station to produce a series of successive sawtooth waves, a plurality of relay tubes under control of said sawtooth waves to select a number of recurrent periods, means to modulate said carrier wave with fragmentary portions of message signals representative of a different message in each recurrent period, said last means comprising a modulation amplifier, and a number of message signal amplifiers, one for each recurrent period, connected in parallel to said modulation amplifier under control of said relay tubes.

9. In a communication system, a radio station, means at said station to produce a series of successive saw tooth waves, a plurality of relay tubes under control of said saw-tooth waves to select a number of recurrent periods, means to receive a modulated carrier wave, means to demodulate said carrier wave and to select in each recurrent period fragmentary portions of message signals representative of a different message, said last means comprising a demodulator, and a number of message signal amplifiers, one for each recurrent period, connected in the output circuit of said demodulator under control of said relay tubes.

10. In a communication system, a radio receiver, apparatus and suitable circuits associated with said receiver to produce a series of successive saw tooth waves under the control of received synchronizing signals, a source of current, a plurality of electron off and on relay tubes each having at least an anode and a cathode connected to said source of current and an electron deflecting electrode controlled by amplitude measurements in each wave of the said saw tooth waves to substantially interrupt the anode cathode current in the several relay tubes in successive rotation, thereby, selecting a number of recurrent periods in said sawtooth waves, means to receive a modulated carrier wave, means to demodulate said carrier wave and to select in each recurrent period

fragmentary portions of message signals representative of a different message, said last means comprising a demodulator, and a number of message signal amplifiers, one for each recurrent period, connected in the output circuit of said demodulator under control of said relay tubes.

11. In a communication system, a transmitter to produce a carrier wave, means associated with said transmitter to produce a series of successive saw tooth waves including control signals for terminating the waves, and a message distributor comprising a number of relay tubes each having at least an anode and a cathode connected to a source of current, and an electron deflecting electrode under the control of said saw tooth waves for deflecting the electrons away from the anode to interrupt current flow in the several relay tubes in sequence, thereby, selecting a number of recurrent periods in the said saw tooth waves for modulating said carrier wave with signals representative of a different message in each recurrent period.

12. In a communication system, means to produce a series of successive saw tooth waves under the control of received synchronizing signals, a message distributor comprising a number of electron deflecting tubes each having at least an anode and a cathode connected to a source of current, and an electron deflecting electrode to deflect electrons away from the anode for interrupting current flow in the several deflecting tubes in sequence, said tubes adapted to allot different periods of time in successive rotation to portions of received signals representative of a number of messages and said control signals.

JOHN H. HOMRIGHOUSE.
